Attorney

UNITED STATES PATENT OFFICE.

FRANKLIN P. KENT, OF LYONS, KANSAS.

HARP.

1,401,158.

Specification of Letters Patent. Patented Dec. 27, 1921.

Application filed July 15, 1920. Serial No. 396,365.

To all whom it may concern:

Be it known that I, FRANKLIN P. KENT, a citizen of the United States, residing at Lyons, in the county of Rice and State of 5 Kansas, have invented a new and useful Harp, of which the following is a specification.

This invention relates to harps of the Dulcimer type wherein a number of strings 10 are provided, these strings being adapted to be vibrated or sounded either by picking them, by striking them, or by operating hammer bars.

One of the objects of the invention is to 15 provide the instrument with strings having bridges so arranged as to divide the strings into groups, a portion of each string being in each group and each of said portions of one string being adapted to produce a tone 20 spaced an octave from that produced by the other portion of the string.

Another object is to so arrange the bridges that, without increasing the number of strings, the range of the instrument can be 25 at least doubled while, at the same time, tones can be produced simultaneously in octaves, thereby to increase the volume.

With the foregoing and other objects in view, which will appear as the description 30 proceeds, the invention resides in the combination and arrangement of parts and in the details of construction hereinafter described and claimed, it being understood that, within the scope of what is claimed, 35 changes in the precise embodiment of the invention shown can be made without departing from the spirit of the invention.

In the accompanying drawings the preferred form of the invention has been 40 shown.

In said drawings—

Figure 1 is a side elevation of the instrument, the same being of a type in which the strings are vibrated by the fingers or by 45 picks.

Fig. 2 is a plan view of the instrument.

Referring to the figures by characters of reference 1 designates the hollow body the end portions of which have parallel side 50 walls, as shown at 2 while the intermediate portion of the body has its side walls bulged outwardly along converging lines as shown at 3. In the top of this intermediate portion of the body are formed apertures 4 through which the sound waves are free to 55 pass from within the body.

Pegs 5 are extended longitudinally from one end of the body while the other end of the body has a transverse flange 6 parallel therewith and spaced therefrom, this flange 60 carrying a series of keys 7. Strings 8 are secured at one end to the pegs 5 and at the other end to the keys 7 and by means of these keys the strings can be adjusted so as to produce the desired tones. All of the 65 strings are extended over two bridges indicated at 9 and 10 respectively. The bridge 9 is set at such an angle relative to the end bridge 11 adjacent the keys 7 that those portions of the strings between the bridges 9 70 and 11 will produce desired tones, such as those of the octave. The bridge 10 is placed where it will contact with the strings at such points that the length of each string between the bridge 9 and the bridge 10 will 75 be exactly double that of the length of the same string between the bridge 9 and the bridge 11. Thus those portions of the strings between the bridge 9 and the bridge 11 will produce tones an octave higher than 80 those portions of the corresponding strings between the bridges 9 and 10. Consequently the range of the instrument is doubled without increasing the number of strings and, at the same time, cords can be played in 85 octaves.

What is claimed is:

1. A musical instrument of the class described including a hollow elongated body, means for attaching strings to the end portions of the body, the means at one end of the body constituting the keys, a transverse bridge at one end of the body, and supplemental bridges extending transversely of the body and coöperating to divide the strings 95 into portions arranged in separate groups, those portions of the strings in one group being adapted to produce tones varying an octave from those portions of the same strings in the next group, there being an 100 opening in the body under each group and communicating with the interior of the body.

2. A musical instrument of the class described including an elongated hollow body, 105 pegs extending longitudinally from one end thereof, a bridge extending transversely of the body at the other end thereof, a flange spaced from the bridge and connected to the body, said flange and bridge being parallel, keys carried by the flange and extending longitudinally of the body below that 110

face thereof on which the bridge is mounted, strings extending longitudinally of the body and fastened at one end to the pegs and at the other end being extended downwardly and fastened to the keys, and supplemental bridges upon the body and engaging the strings, said bridges being arranged relative to each other so as to separate each string into two sound producing portions, the tone produced by one portion of each string being separated by an octave

from the tone produced by the other portion thereof, there being openings in the body between the bridges.

In testimony that I claim the foregoing 15 as my own, I have hereto affixed my signature in the presence of two witnesses.

FRANKLIN P. KENT.
